UNITED STATES PATENT OFFICE.

HENRIETTA F. DUKE, OF NEW YORK, N. Y., ASSIGNOR TO THE BUTTERICK PUBLISHING COMPANY, (LIMITED,) OF SAME PLACE.

DESIGN FOR A LADY'S COSTUME.

SPECIFICATION forming part of Design No. 18,246, dated April 10, 1888.

Application filed February 23, 1888. Serial No. 265,057. Term of patent 3½ years.

To all whom it may concern:

Be it known that I, HENRIETTA F. DUKE, of the city, county, and State of New York, have invented and produced a new and original Design for a Pattern of a Lady's Tennis Costume; and I do hereby declare that the engraved prints accompanying this specification convey to any one accustomed to using paper patterns a clear understanding of how a garment made up by the pattern will appear.

The design shows a round walking-skirt and waist. The skirt displays a flat drapery extending to its lower edge all around; a short round tablier drapery exhibiting draping 15 plaits in its side edges; a full back drapery that falls in straight plaits to the edge of the skirt at the right side, presents a rounding outline at the left side where it falls in jabot

folds, and exhibits loopings near the top. The waist exhibits close-fitting fronts closing 20 at one side of the center and displaying a surplice ornament on either side, a close-fitting back, a sailor-collar falling over the tops of the surplices, coat-sleeves, and a belt that shapes a point at the top and bottom of the 25 center of the front.

What I claim as my invention, and desire to secure by Letters Patent, is—

The design for a lady's tennis costume, as shown in the engraved prints accompanying 30 this specification.

HENRIETTA F. DUKE.
